UNITED STATES PATENT OFFICE.

PHILIP S. DELANY, OF KANSAS CITY, MISSOURI, ASSIGNOR TO UNIVERSAL VENTILATING COMPANY, OF KANSAS CITY, MISSOURI, A CORPORATION OF MAINE.

BRACKET.

1,113,884.

Specification of Letters Patent. Patented Oct. 13, 1914.

Application filed October 8, 1912. Serial No. 724,501.

To all whom it may concern:

Be it known that I, PHILIP S. DELANY, a citizen of the United States, residing at Kansas City, in the county of Jackson and State of Missouri, have invented certain new and useful Improvements in Brackets; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 My invention relates to brackets, and more particularly to a bracket for use in supporting deflectors in a window ventilator; the principal object of the invention being to provide a two piece bracket, the members of 20 which may slide over each other to adjust a deflector carried by one of the members, and comprising a friction brake for holding the members in adjusted position. In accomplishing these objects I have provided 25 the improved details of structure herein- after described and illustrated in the accompanying drawings, wherein:—

Figure I is a perspective view of a pair of brackets containing my improvements and 30 illustrating their use in supporting a screen and deflector of a window ventilator. Fig. II is a vertical section of the parts shown in Fig. I. Fig. III is an enlarged detail perspective of a part of one of the brackets on 35 the line III—III, Fig. II. Fig. IV is a vertical section on the line IV—IV, Fig. III.

Referring more in detail to the parts: 1 designates a window frame, 2 the sill and 3 a sash, of any ordinary construction. Fixed 40 to each side of frame 1 is a wedge-shaped stationary bracket member 4, the lower edge of which sits flush on the sill, the upper edge having a curved, inturned lip 5 provided with a depending flange 6 forming a 45 downwardly opening groove 7.

At the outer edge of the body member are inturned vertical flanges 8 which are spaced to form a groove 9 for receiving a screen member, presently described.

50 Pivottally mounted on a pin 10 which extends through the lower end of the stationary member 4, and into the window frame, is a movable bracket member 11 having a curved lip 12 on its upper end provided with

a depending flange 13, forming a downwardly facing groove 14 similar to the groove 7 on the stationary member, the outer end of the flange 13 having a laterally directed stop boss 15 adapted for engaging a depending boss 16 on the inner end of the 60 stationary flange 6 to limit the inward pivotal movement of the movable bracket member.

Fixed to the inturned lip 12 is a spring 17, which is preferably flat and has a bearing 65 head 18 projected outwardly from the outer end of the lip 12 and adapted to bear against the under face of the lip 5 of the stationary member, to form a friction brake whereby the movable member may be held in any set 70 position.

At the inner edge of the movable member are inturned, vertical flanges 20 which are spaced to form a vertical groove 21 for receiving a deflector, presently described.

75 The bracket just described is duplicated on the opposite window frame so that the grooves 9—21 in opposite brackets face each other.

22 designates a deflector, preferably of 80 plate glass, which is slidably mounted in the grooves 21 in the movable bracket members so that it may be removed from and placed in the bracket when desired.

Similarly mounted in the vertical grooves 85 9 on the stationary member is a screen 23 which is preferably formed in sections and provided with slide brackets 24 whereby the sections may be moved longitudinally relative to each other to adapt the screen to the 90 brackets and close the outer side of the ventilator, to filter air coming in through the window opening and perform the usual functions of a screen.

It is apparent that by having the screen 95 longitudinally adjustable, a stock size may be made so that the brackets may be set in frames of different width, the glass cut to fit the brackets and the adjustable screens fitted within their grooves, in this way saving the expense of manufacturing screens of different length.

Presuming the parts to be assembled as described, it is apparent that when the window is open to the extent illustrated, air 105 coming in through the opening must pass through the screen to filter dust therefrom, and that after the air passes through the

screen it impinges against the deflector and is directed upwardly into the room to obviate lateral drafts and distribute fresh air.

When a maximum volume of fresh air is desired, the bracket is pivoted inwardly to its fullest extent to enlarge the intake and lower the angle of deflection, and when a less quantity of air is desired the movable brackets are pivoted outwardly to reduce the intake opening and raise the angle of deflection, so that a draft will be less likely to strike a person in a room.

By means of my friction brake, the deflector may be easily manipulated without 15 catches, or the like.

Having thus described my invention, what I claim as new therein and desire to secure by Letters Patent, is:—

1. A bracket comprising movably related members, one having a keeper and the other a slide adapted for travel in the keeper, and a friction device on one of the members yieldingly wiping the other member, for the purpose set forth.
2. A bracket comprising movably related members, one having a keeper and the other a slide adapted for guided travel in the keeper, and a flat spring on one of said members yieldingly and constantly engaging the other member, for the purpose set forth.
3. A bracket comprising movably related members, one provided with an overhanging keeper and the other with a slide underlying the keeper, and a flat spring on one of said members yieldingly engaging the other member, for the purpose set forth.
4. A bracket comprising movably related members, one having a lateral lip and depending flange forming a keeper hood, the other having a lateral lip and depending flange located within like parts of the first named member and slidable therein, and a resilient member fixed to one of said mem-

bers and yieldingly engaging the other, for the purpose set forth.

5. A bracket comprising movably related members, one having a lateral lip and depending flange forming a keeper hood, the other having a lateral lip and depending flange located within like parts of the first 50 named member and slidable therein, a resilient member fixed to one of said members and yieldingly engaging the other, and a flat spring fixed to the under side of the slide lip and having a free portion extended 55 upwardly to engagement with the keeper lip.

6. A bracket comprising movably related members, one having a lateral lip and depending flange forming an overhanging keeper hood, the other having a like lip 60 and flange located within the keeper hood and slidable relative thereto; the inner lip being slotted transversely, and a flat spring fixed to the under side of the inner lip and having its free end projected through said 65 slot to engagement with the keeper lip.

7. A bracket comprising movably related members, one comprising a transverse lip having a depending flange, and having a stop boss depending from one end of the 70 flange; a second member pivotally connected with the first member and having a like lip and flange, the last named flange having a laterally directed stop boss adapted for engagement with the boss on the first named 75 flange to limit pivotal movement of the parts, and a friction member fixed to one of said members in wiping engagement with the other member, for the purpose set forth.

In testimony whereof I affix my signature 80 in presence of two witnesses.

PHILIP S. DELANY.
